(57) **CLAIM**

The ornamental design for a connector for expanded cell confinement web with polygon handle, as shown and described.

DESCRIPTION

FIG. 1 is a top perspective view of an embodiment of my new design;

FIG. 2 is a bottom perspective view of the connector of FIG. 1;

FIG. 3 is a front elevational view of the connector of FIG. 1;

FIG. 4 is a rear elevational view of the connector of FIG. 1; FIG. 5 is a right elevational view of the connector of FIG. 1;

FIG. 6 is a left elevational view of the connector of FIG. 1; FIG. 7 is a top plan view of the connector of FIG. 1; and, FIG. 8 is a bottom plan view of the connector of FIG. 1.

The dash-dash broken lines are included for the purpose of illustrating portions of the connector for expanded cell confinement web with polygon handle and forms no part of the claimed design. The dot-dash lines define the bounds of the claimed design and form no part thereof.
